EXERCISING APPARATUS

Filed April 23, 1925

INVENTOR.
GIOVANNI V. ROSI.
By Martin P. Smith
Atty.

Patented Feb. 22, 1927.

UNITED STATES PATENT OFFICE.

GIOVANNI VITTORIO ROSI, OF LOS ANGELES, CALIFORNIA.

EXERCISING APPARATUS.

Application filed April 23, 1925. Serial No. 25,289.

My invention relates to an improved exercising apparatus and has for its principal object, the provision of a relatively simple and practical apparatus that will enable the user to indulge in physical exercise that is highly beneficial to practically all parts of the body and particularly the abdominal and pelvic regions, as well as the hips, thighs and all parts of the lower limbs.

10 A further object of my invention is, to provide, in a suitable compact structure, which in addition to serving as an exercising apparatus may be advantageously used as an aid in the teaching of dancing, as 15 an orthopedic apparatus, and as a gymnasium appliance.

Further objects of my invention are to provide an apparatus of the character referred to that occupies relatively little floor space when set up for use and which may be folded into a compass of small area when packed for storage or transportation.

With the foregoing and other objects in view, my invention consists in certain novel features of construction and arrangement of parts that will be hereinafter more fully described and claimed and illustrated in the accompanying drawings in which:

Fig. 1 is a front elevational view of an exercising apparatus of my improved construction.

Fig. 2 is an end elevational view of the apparatus.

Fig. 3 is an enlarged vertical section taken on the line 3—3 of Fig. 1.

Fig. 4 is an enlarged horizontal section taken on the line 4—4 of Fig. 1.

Fig. 5 is an enlarged detail section taken on the line 5—5 of Fig. 3.

Fig. 6 is a detail section taken on the line 6—6 of Fig. 2.

Fig. 7 is an enlarged detail section taken on the line 7—7 of Fig. 2.

Fig. 8 is a plan view of the right hand end of the apparatus.

My improved exercising apparatus includes an upright frame composed of a base rail 10, from which arise end posts 11 and a center post 12 and connecting the upper end of said center post and the upper portions of said end posts is a top rail 13.

Arranged between center post 12 and end posts 11, between base rail 10 and top rail 13, are horizontally disposed rails 14 that are suitably spaced apart.

Connected by hinges 15 to the upper front

edge of base rail 10 is the upper rear corner of a foot board 16, the upper surface of which is preferably inclined and covered with a thin sheet of rubber or the like, to provide firm footing for the user of the apparatus.

Connected by hinges 17 to the inner rear corners of each end post 11 is the inner upright rail of a substantially A-shaped end frame 18 which, when the apparatus is set up for use projects rearwardly from the end of the upright frame and provides a brace therefor. In order to securely anchor the apparatus to the floor, suitable angle 70 plates 19 of metal are fixed by means of screws to the floor and to the ends of the base rail 10 and the lower end of the rear rail of brace frame 18.

When the device is packed for storage or transportation, foot board 16 is swung upward against the lower portions of posts 11 and 12, as illustrated by dotted lines Fig. 2, and end frames 18 are swung inwardly 80 against the end portions of the upright frame, as illustrated by dotted lines Fig. 8.

Passing through openings that are formed in the upper portions of end posts 11 is a horizontally disposed hand rail 20 that is securely retained in position by screws 21 85 that pass through the upper ends of the end posts and engage in apertures that are formed in said hand rail (see Fig. 6).

Substantially rectangular panels 22 are arranged for horizontal sliding movement 90 between the rails 14 to the sides of center post 12 and the front portions of end rails 11 are cut away as designated by 23 for the accommodations of these sliding panels.

The outer faces of the sliding panels 22 95 are provided with leather or fabric covered pads 24.

Formed in the upper and lower edges of panel 22 are grooves 25, and seated therein are anti-friction bearings 26 that engage 100 rails 27 and which latter are secured respectively to the lower face of the upper one of rails 14 and to the upper face of the lower end of said rails.

Arranged on the rear face of panel 22 105 are metal straps 28 which, as the panels move between their guiding means, bear on anti-friction rollers 29 that are arranged in the front faces of the cutaway portions 110 23 of end posts 11.

The inner ends of retractile springs 30 are secured to center post 12 and the outer ends

of said springs are secured respectively to the outer portions of the rear faces of panels 22.

In the use of my improved exercising apparatus, the feet of the user are placed with toes pointing outwardly on the end portions of the inclined upper face of foot board 16 with the knees bearing against the central portions of pads 24 on panels 22, the body in an upright position and with the hands grasping hand rail 20.

The user now, with a comparatively slow movement gradually lowers the body, then raises same and, at the same time pressing 15 the knees against the sliding panels and keeping the torso in a substantially vertical position.

Obviously, these vertical movements flexes all of the muscles and ligaments of the abdomen, pelvis and lower limbs and the pressure of the knees against the padded panels causes the latter to slide backward and forward between their guides, thereby producing yielding pressure against the knee 20 joints that tends to straighten the limbs and correct such irregularities known as bowlegs and knock knees.

As an aid in the teaching of dancing, the use of the apparatus trains and prepares 30 the lower limbs and feet to execute with ease and precision, the movements of the classical dances as fundamentally taught by the ancient Greeks, and upon which all other forms of dancing are based.

As an orthopedic appliance, the use of the device gradually corrects many of the irregularities often found in the articulations of the feet and ankles, reinforcing and giving elasticity to the ligaments, strengthening 35 the muscles, and restoring the bones to their proper positions.

As an exercising apparatus in the home or gymnasium, the use of the appliance brings about a harmonious development of 45 the lower abdominal and pelvic muscles, bones and ligaments; also the hips, lower limbs and feet, preventing, remedying or suppressing some natural or acquired irregularity, and at the same time strengthening 50 the exercised muscles and imparting to the lower limbs and feet, the proper or normal anatomical shape.

It will be understood that minor changes in the size, form and construction of the 55 various parts of my improved exercising apparatus may be made and substituted for those herein shown and described without

departing from the spirit of the invention, the scope of which is set forth in the appended claims.

I claim as my invention:

1. In an exercising apparatus, an upright frame, horizontally disposed bearings on said frame and a pair of spring held panels arranged for sliding movement upon said 60 bearings.

2. In an exercising apparatus, an upright frame, a pair of spring held panels, horizontally disposed anti-friction bearings arranged on the frame and supporting said panels, and an inclined foot board arranged in front of the base portion of said upright frame. 70

3. In an exercising apparatus, an upright frame, a pair of spring held panels, horizontally disposed anti-friction bearings arranged on the frame and supporting said panels, an inclined foot board arranged in front of the base portion of said upright frame and a hand rail arranged at the upper portion of said frame. 75

4. In an exercising apparatus, an upright frame, a pair of spaced horizontally disposed rails forming a part of said frame, anti-friction bearings on said rails and spring held panels mounted for sliding 80 movement upon said bearings.

5. In an exercising apparatus, an upright frame, a pair of spaced horizontally disposed rails forming a part of said frame, spring held panels arranged between said 90 rails and anti-friction bearings arranged between said rails and said sliding panels.

6. In an exercising apparatus, an upright frame, a pair of spaced horizontally disposed rails forming a part of said frame, spring held panels arranged between said 95 rails, anti-friction bearings between said rails and panels, and an inclined foot board secured to and disposed in front of the lower portion of said upright frame.

7. In an exercising apparatus, an upright frame, a pair of spaced horizontally disposed rails forming a part of said frame, spring held panels arranged between said rails, anti-friction bearings between said rails and panels, an inclined foot board secured to and disposed in front of the lower portion of said upright frame and a hand rail arranged at the upper portion of said upright 100 frame.

In testimony whereof I affix my signature.

GIOVANNI VITTORIO ROSI.
